COMBINED BUMPER, GRILLE, AND LAMP UNIT FOR AN AUTOMOBILE

Jack E. Kenitz, Detroit, and Richard F. Baird, Oak Park, Mich., assignors to Chrysler Corporation, Highland Park, Mich., a corporation of Delaware

Application August 5, 1957, Serial No. 47,209

Term of patent 7 years

(Cl. D14—18)

Fig. 1 is a front view of a combined bumper, grille and lamp unit for an automobile embodying our new design;

Fig. 2 is a side elevation thereof; and

Figs. 3 and 4 are sectional views taken on the lines 3—3 and 4—4 of Fig. 1.

We claim:

The ornamental design for a combined bumper, grille and lamp unit for an automobile, substantially as shown.
